MAGAZINE RACK

Roger K. Ericson, 906 W. Miner St.,
Arlington Heights, Ill. 60005

Filed Dec. 18, 1967, Ser. No. 9,815

Term of patent 7 years

U.S. Cl. D33—2
Int. Cl. D6—01

FIGURE 1 is a side elevational view of the magazine rack showing my new design.

FIGURE 2 is a side elevational view of the magazine rack looking in the direction of the arrows 2—2 of FIGURE 1.

FIGURE 3 is a top plan view thereof.

I claim:

The ornamental design for a magazine rack, as shown.
